UNITED STATES PATENT OFFICE

158,932

COMBINED BOWL AND NUTCRACKER

Ernest J. Carlson, Reading, Pa.

Application October 14, 1948, Serial No. 149,111

Term of patent 14 years

(Cl. D44—1)

To all whom it may concern:

Be it known, that I, Ernest J. Carlson, a citizen of the United States, residing at Reading, in the county of Berks and State of Pennsylvania, have invented a new, original, and ornamental Design for a Combined Bowl and Nut Cracker of which the following is a specification, reference being had to the accompanying drawing, forming part thereof.

In the drawing:

Fig. 1 is a perspective view of a combined bowl and nut cracker showing my new design,

Fig. 2 is a plan view of the same,

Fig. 3 a side elevation thereof,

Fig. 4 an end view, and

Fig. 5 a cross sectional view on the lines 5—5 of Fig. 3.

The dominant features of the design reside in the nut cracker unit substantially as shown.

I claim:

The ornamental design for a combined bowl and nut cracker, as shown and described.

ERNEST J. CARLSON.
